MACHINE FOR FORMING MATERIAL BY A PULSED, HIGH INTENSITY MAGNETIC FIELD

David F. Brower and Gamon B. Hayward, San Diego,
Calif., assignors to General Dynamics Corporation, New
York, N.Y., a corporation of Delaware

Filed Apr. 18, 1962, Ser. No. 69,762

Term of patent 14 years

(Cl. D26—1)

FIG. 2

FIG. 1

FIG. 3

FIGURE 1 is a perspective view of a machine for forming material by a pulsed, high intensity magnetic field showing our new design;

FIGURE 2 is a reduced plan view thereof; and

FIGURE 3 is an opposite perspective view thereof.

The dominant features of our new design reside in the portion shown in full lines.

We claim:

The ornamental design for a machine for forming material by a pulsed, high intensity magnetic field, substantially as shown and described.
